UNITED STATES PATENT OFFICE.

FRANCIS J. STRAUB, OF NEW KENSINGTON, PENNSYLVANIA.

MEASURING BOX.

Application filed February 1, 1927. Serial No. 165,238

My invention consists of an improvement in measuring boxes for concrete mixing machines and similar apparatus.

It has in view to provide a measuring box of such kind for materials which are handled in lump or powdered form, as, for instance, the raw material for making aggregate for concrete construction in article or bulk form.

In the particular use of the invention involved, it is particularly designed for measuring the raw aggregate, or cement, or both, for delivery to a mixer, in the manufacture of building blocks and the like. It may be used, however, in connection with various kinds of material, the primary object being to provide a simple, rapidly operative means for periodically delivering a measured amount from a source of supply to a utilizing machine.

20 In the drawings:

Fig. 1 is a view partly in elevation and partly in section, showing the mixing box in relation to a hopper and mixer, the section being on the line I—I of Fig. 2;

25 Fig. 2 is a cross section on the line II—II of Fig. 1;

Fig. 3 is a view similar to Fig. 2, showing the measuring box tilted for delivery and also showing the adjustable wall shifted inwardly;

30 Fig. 4 is an enlarged sectional detail view on the line IV—IV of Fig. 2.

Referring to the drawings, A is the delivery end of a hopper adapted to discharge raw material into the movable measuring box for charging measured amounts into the shell of a mixer B or the like. Extending laterally from the side of the mixer is an inclined shelf 2, connected therewith and properly supported, forming a receiving platform or bottom for the measured material, from which it is shifted into the mixer upon tilting of the measuring box.

Said box as shown comprises a rectangular vessel or chamber having end walls 3—3 of plate metal, a front fixedly connecting wall 4, and a rear adjustable wall 5. Front wall 4 is connected with the end plates 3 vertically along the inner edges thereof by means of an angle member 6, securely riveted or bolted to the end plates and wall respectively, as clearly shown.

The wall 4 is preferably slotted, as at 7, for a limited amount of vertical adjustment

on the angles 6, to adapt it to a substantially close relation to the inclined shelf 2.

The lower edges of the end walls 3 substantially conform to the inclination of shelf 2, being slightly rounded, as at 8, for clearance in swinging inwardly.

Rear wall 5 is fixedly connected by rivets or bolts with endmost angle members 9, which are pivotally connected at 10 by bolts with the lower inner edge portions of the end plate, for inward or outward swinging. End plates 3 are provided with slots 11, for adjustable connection by bolts 12, extending through angles 9, so that the rear wall 5 may thus be adjusted throughout the length of slots 11 at each end and then fixedly secured, 70 for varying the amount of cubical contents of the measuring box. Such adjusted position is shown in Fig. 3.

The rear walls 5 are provided with cover plates 13 of angle form, secured to the opposite ends of the wall 5, as in Fig. 4, and close the slots 11 against escape of material therethrough in any position of the wall.

A cut off plate 14 is adjustably connected by its terminal angles 15 and slots 16 therethrough and bolts 17, so that the plate 14 may be set inwardly or outwardly a limited degree, to adjust it to proper cut-off relationship with the delivery end of hopper A, as it is swung to a delivery position, to terminate the flow from the hopper, as in Fig. 3.

The measuring box as a whole is pivotally mounted by its middle cross shaft 18, extending through the end walls and hubs 19 thereof into supporting bearings 20, depending 90 from framing timbers 21 of a building or the like. The measuring box is provided with one or more operating handles 22 secured to one or both of the end plates, by which the measuring box may be tilted.

The construction and operation of the invention will be readily understood and appreciated by all those familiar with the making and use of concrete aggregate or similar materials.

When in registering position, as in Fig. 2, the raw material will flow by gravity from the hopper, and will fill the box from the bottom shelf 2 upwardly to its top, sloping approximately from each lower edge of the hopper terminal at an angle of about 45°, as in usual mineral distribution. When thus filled, the measuring box is shifted with its

open bottom inwardly over across the shelf 2 of mixer B, while the top, at the same time, is shifted in the reverse position, bringing the cut-off plate 14 underneath the hopper opening and effectually closing off further supply.

The contents will immediately fall by gravity into the mixer, whereupon the box will be shifted back to receiving position, the operation being repeated periodically as often as desired.

The adjustable wall 5 may be accurately set to vary the desired contents of the box, so that at each operation a definitely known amount is delivered. The upper end of the measuring box being open, as shown, gives ample opportunity for observation by the operator to see when it is full, and the material will not overflow because of the natural termination of the flow upon being filled.

20 Its construction is simple and compact, and requires comparatively little height above the mixer when used to measure aggregate or cement and deliver the measured material thereto.

25 It is comparatively simple and cheap in construction and easy to operate, having no small parts to become damaged or worn.

The adjustability to different capacities and its low cost of manufacture are further 30 advantages, while it is self-cleaning and not apt to contain any adhering material when emptied.

The bottom shelf 2 being attached in forming a part of the mixer B, receives a certain 35 amount of transmitted vibration from the mixer itself, assisting the material in settling and packing, thus ensuring uniform consistency and definite equally measured amounts.

40 The invention may be changed or varied in different detail construction, or in size and capacity to adapt it to varying conditions of use, but all such changes are within the province of the skilled mechanic, and are contemplated as within the scope of the following claims.

What I claim is:

1. The combination with an upper open bottom hopper and a lower receiving casing 50 having a laterally extending material supporting shelf, of an interposed pivotally mounted measuring box having an adjustable side wall, a cut off gate for the hopper and a continuously open bottom, and means

for shifting the measuring box on its pivotal mounting to move contained material from direct supporting engagement with the shelf to the casing. 55

2. A measuring box for the purpose described consisting of end plates, intervening side plates, means for adjusting one of said side plates, an upper adjustable cut off gate extending between the end plates for controlling supply to the box, a pivoting shaft for tilting movement of the box thereon extending beyond the end plates at each end, and a shifting lever for the box. 60

3. In a measuring box of the class described, the combination with end plates, a side plate connecting the end plates, an opposite side plate pivotally mounted between the end plates and having adjustable connection with the end plates, an upper cut off gate extending between the end plates for controlling supply to the box, a supporting shaft extending endwise through the box for tilting movement thereon, and an operating lever secured to the measuring box. 70

4. The combination with an upper open bottom hopper and a lower receiving casing 80 having a laterally extending supporting shelf, of an interposed pivotally mounted measuring box open at top and bottom having at its top an independently adjustable cut-off gate movable with and mounted partly across the upper portion of the box between its sides and means for shifting the measuring box and its cut-off gate on the pivotal mounting to move contained material from supporting relation with the shelf to the casing while moving the cut-off gate beneath the hopper bottom. 90

5. The combination with an upper open bottom hopper and a lower receiving casing 95 having a laterally extending material supporting shelf, of an interposed pivotally mounted measuring box open at top and bottom consisting of end plates, a fixedly connected side wall, an opposite inwardly and outwardly adjustable side wall, a cut-off gate 100 for the hopper, and means for shifting the measuring box on its pivotal mounting to move contained material from direct supporting engagement with the shelf to the casing. 105

In testimony whereof I hereunto affix my signature.

FRANCIS J. STRAUB.
